APPARATUS FOR SILENCING THE EXHAUST
OF INTERNAL COMBUSTION ENGINES

Joseph Louis Lascroux, Marseille, France

Application October 26, 1935, Serial No. 46,837
In France November 27, 1934

4 Claims. (Cl. 181—69)

This invention relates to apparatus for silencing the exhaust of internal combustion engines.

It is generally known that the exhaust gases leaving the cylinders of an internal combustion engine are still under such pressure that their expansion into the atmosphere produces the disagreeable noise with which everybody is acquainted.

In land vehicles driven by internal combustion engines of relatively low power, it has been found possible by means of exhaust boxes to expand sufficiently these burnt gases to the point of obviating the noise of the exhaust, but the same is not the case with engines of much greater power, including those used in aviation.

It is also commonly known that the escape of the gases from an aeroplane reveals its presence by its noise, although the aeroplane is not visible. This noise is extremely disagreeable to the passengers, who must bear it during the whole of the journey, whereby any conversation between them is rendered practically impossible.

It will thus be realized that the expansion of the burnt gases upon leaving the exhaust pipe is one of the serious drawbacks of mechanical aerial locomotion.

A solution of the problem set out, i. e. the suppression of the exhaust noise, is afforded by the subject of the present invention, which resides in a cellular apparatus for the silent discharge of the gases leaving internal combustion engines.

The invention has for one object to obviate completely the noise caused by the escape of the burnt gases owing to their expansion into the atmosphere, use being made of very simple means for obtaining a free and silent escape in all internal combustion engines.

The invention has for a further object to provide apparatus for silencing the exhaust of external combustion engines and for like purposes, comprising an expansion chamber adapted to be inserted between the ends of a gap in the pipe through which the exhaust gases flow, a first group of compartments formed in the inlet end of said chamber and opening into the interior of the same, means for connecting all of said compartments with the end of said pipe connected with the inlet to the expansion chamber, a second group of compartments formed in the outlet end of said chamber and opening into the interior of the same, and means for connecting all of the compartments of said second group with the end of said pipe connected with the outlet end of the expansion chamber.

Other objects will become apparent from the

description of the annexed drawing, which now follows, and from the appended claims.

The drawing shows, by way of example only, one of the forms of the subject of the invention, and

Figure 1 shows a front view and a side view respectively of a blade grouped with other identical blades and thereby constituting the cells or compartments.

Figure 2 illustrates, in a longitudinal sectional view, the interior arrangement of the cellular apparatus for the silent discharge of the burnt gases leaving an internal combustion engine.

Figure 3 is the exterior view thereof.

Figure 4 shows, in perspective, the same apparatus as is illustrated in Figure 2, a portion of the jacket being removed; this figure is given to assist in understanding the functioning of the apparatus.

This apparatus is based on the principle of the division of the currents of gas and their expansion, which is obtained without any form of baffles. It is constituted by semi-circular blades 2 (Figure 1) having an aperture 3 of the same shape. These blades are judiciously grouped, in numbers varying according to the power of the engine, inside a jacket 4 (Figure 2) etc., preferably of cylindrical shape. Each group of blades is in communication through its aperture 3 with a somewhat spoon-shaped portion of tube 5, which is integral with the inlet pipe 6 for the burnt gases.

At the rear of the first group of blades 2, is situated an expansion chamber 7, the volume of which is also proportional to the power of the engine. Following this chamber is situated another group of blades 2, the apertures 3 of which are also in communication with the portion of tube 8, the form of which is identical with that of 5 and which is integral with the pipe 9 for the discharge into the atmosphere of the completely expanded burnt gases. Each group of blades forms an expansion stage, these stages being more or less numerous according to the volume of the gases to be expanded and therefore not being limitative.

When constituted in this manner, this apparatus functions as follows:

The burnt gases arrive in the apparatus through the pipe 6, and on reaching the cupola-shaped apertures and the edges of the blades 2 forming an equal number of cells, they become divided by penetrating into the latter in the direction of the arrows 10 (Figures 1, 2 and 4) and leave each of these cells forming expansion

chambers in the direction of the arrows 11, they then arrive thus divided, expanded and cooled in part in the large collecting chamber 1, where they are subjected to a second expansion. The gases 5 then leave this chamber, passing in the direction of the arrows 12 into further cellular expansion chambers formed by other blades 2 identical to the first; the gases then follow the direction of the arrows 13 and escape through the pipe 9 into 10 the atmosphere completely expanded and without noise.

It will be seen that, owing to this arrangement, the flow of gases is sub-divided into as many thin streams as there are blades and that they 15 can only escape towards the outlet by traversing a further group of blades, thereby carrying out a semi-gyratory movement which contributes to the effectiveness of the functioning. It will also be seen that the section of the passage of the 20 gases into the silencing apparatus is always greater than the section of the pipes of the engine and that there exists no throttling of the passage of the gases which is likely to set up a counter-pressure in the apparatus, or a braking of the 25 motor, so that no power is absorbed.

The utilization of this apparatus at the outlet of the gases of an internal combustion engine realizes great industrial progress in this type of device, as it is comparatively effective in 30 suppressing noise. This feature is of considerable importance for aviation, since in the event of war it enables machines to reach objectives without revealing their presence, and enables passengers to complete their journey in greater comfort. It 35 obviates all back-firing and therefore makes absolute security, and in addition has the essential feature of obviating the visibility of aeroplanes at night owing to flames or flashes from the exhaust. To these advantages are added those of 40 greater facility of dismantling and lightness rendering it suitable for aviation.

However, the forms and dimensions of this apparatus, as well as the materials used in its construction may vary without thereby departing 45 from the scope of the invention which has hereinbefore been described.

What I claim and desire to secure by Letters Patent of the United States is:—

1. Apparatus for silencing the exhaust of 50 internal combustion engines and for like purposes, comprising an expansion chamber adapted to be inserted between the ends of a gap in the pipe through which the exhaust gases flow, a first group of similar compartments forming a series 55 located in the inlet end of said chamber and individually opening into the interior of the same, means for connecting all of said compartments with the end of said pipe connected with the inlet to the expansion chamber, a second group of 60 similar compartments forming a series located in the outlet end of said chamber and also individually opening into the interior of the same, and means for connecting all of the compartments of said second group with the end of said pipe con-

nected with the outlet end of the expansion chamber.

2. Apparatus for silencing the exhaust of internal combustion engines and for like purposes, comprising an expansion chamber adapted to be 5 inserted between the ends of a gap in the pipe through which the exhaust gases flow, extensions of the ends of said pipe projecting into the body of said chamber, a first group of similar compartments forming a series located between one of 10 said extensions and the interior walls of said chamber and individually opening into the latter, a closure at the end of the extension of said pipe and an orifice in said extension simultaneously opening individually into all of said compartments in the first group or series, a second group 15 of similar compartments forming a series located between the other of said extensions and the interior walls of said chamber and individually opening into the latter, a closure at the end of said other extension and an orifice in said other extension simultaneously opening individually into all the compartments of said second group.

3. Apparatus for silencing the exhaust of internal combustion engines and for like purposes, 20 comprising an expansion chamber adapted to be inserted between the ends of a gap in the pipe through which the exhaust gases flow, extensions of the ends of said pipe projecting into the body of said chamber, a first series of spaced plates secured in said chamber to form a first group of 25 compartments therein and located between one of said extensions and the interior walls of said chamber said compartments opening into the latter, a closure at the end of the extension of said pipe and an orifice in said extension opening into all of said compartments, a second series of 30 spaced plates secured in said chamber to form a second group of compartments and located between the other of said extensions and the interior walls of said chamber said second group opening into the latter, semi-cupola shaped portions on all 35 the plates of both first and second series, closures upon the ends of both said extensions, and an orifice in each of said extensions allowing said 40 semi-cupola shaped portions to depend therein.

4. Apparatus for silencing the exhaust of internal combustion engines and like purposes, comprising a cylindrical expansion chamber 45 adapted to be inserted between the ends of a gap in the pipe through which the exhaust gases flow, extensions of the ends of said pipe projecting into the body of said chamber, a first group of semi-circular plates each having a raised semi-cupola shaped portion located at their geometric 50 centre and being spaced apart and secured within said chamber between one of the extensions and the walls of said chamber, a second series of similar plates similarly arranged with respect to the other extension, a closure at the inner extremity 55 of both said extensions, and an orifice in each of the latter into which said semi-cupola shaped portions depend.

JOSEPH LOUIS LASCROUX.
